AIRFOIL WARPING FIXTURE

Shakespeare O. Goldsmith, Detroit, Mich.

Application April 7, 1955, Serial No. 499,813

4 Claims. (Cl. 153—78)

This invention relates to a warping fixture and more particularly to a blade warping fixture for blades of the type as might be used upon the stator of an impeller, or the rotor of a turbine.

Heretofore in a construction of blades of this type the finally constructed blade is formed with a longitudinal 20 twist formed therein of a predetermined amount.

There has long existed the difficulty of inexpensively and effectively forming and warping the initially cast blades or forged blades to a correct predetermined shape.

It is the object of the present invention to provide a blade warping fixture which is adapted for attachment to a blade blank and which is adapted to draw the blade through a pair of surface forming rollers which operatively engage opposite sides of the blade body as the blade is drawn therethrough.

It is the object of the present invention to provide a novel ram construction by which the said blade is longitudinally drawn through the forming rollers, together with novel mechanism for effecting a rotary movement of the ram as it is withdrawn longitudinally to thereby impart to the blade a predetermined angular twist along the line of warp point or center of gravity.

In view of the inherent characteristic of the metal from which the particular blade is formed and its inherent resiliency, consideration must be given to effecting a twisting action in excess of the final twist desired for the reason that there will be a partial return movement of the blade towards its original condition.

It is, therefore, the further object of the present invention to provide a mechanism whereby the amount of twist of the ram or drawbar may be regulated and accurately controlled.

It is the further object of the present invention to provide a pair of hydraulically or pneumatically operated rollers which are adapted to cooperatively engage opposite sides of the blade blank and compressively engage the same for firmly retaining and guiding the blade as it is drawn through the said rolls.

It is the further object of the present invention to provide a pair of complementary shaped rolls adapted to engage opposite upright surfaces of the blade and which conform to a predetermined contour or cross-sectional shape in the said blade as it is initially forged or cast or otherwise delivered to the warping fixture.

It is the further object of the present invention to provide means for permitting easy interchanging of rollers depending upon the size and contour of the particular blade to be warped.

It is the further object of the present invention to provide a central control mechanism in conjunction with the operation of the hydraulic or pneumatic cylinders for effecting simultaneous inward movement and continuous operative engagement of the said rollers with respect to the blade to be warped, together with means for automatically withdrawing the said rollers upon release of pressure to the said cylinders.

These and other objects will be seen from the follow-

ing specification and claims in conjunction with the appended drawings, in which:

Fig. 1 is a side elevational view of a blade blank.
Fig. 1-A is a section taken on line 1A—1A of Fig. 1.
Fig. 2 is a plan view thereof.

Fig. 3 is a diagrammatic indication indicating the intersecting planes corresponding generally to the longitudinal axis of the blade blank as contrasted with the respective longitudinal axes after the blade warping operation.

Fig. 4 is a fragmentary plan view of the present blade warping fixture.

Fig. 5 is a side elevational view thereof, fragmentarily shown, taken on line 5—5 of Fig. 4, partially broken away and sectioned for illustration.

Fig. 6 is a left end elevational view taken on line 6—6 of Fig. 5, being a fragmentary illustration.

Fig. 7 is a fragmentary right end elevational view taken on line 7—7 of Fig. 4.

Fig. 8 is a fragmentary elevational section of a different form of blade securing adaptor.

Fig. 9 is a side elevational view of one of the movement limiting collars which are secured to the drawbar in longitudinally spaced relation.

Fig. 10 is a fragmentary illustration showing the method of locking the blade securing adapter to the end of the drawbar in exacting relation to center of gravity of airfoil.

Fig. 11 is an end elevational view of the adapter shown in Fig. 8.

Fig. 12 is a fragmentary elevational section illustrating a motor for reciprocating the drawbar.

It will be understood that the above drawings illustrate merely a preferred embodiment of the invention and that other embodiments are contemplated within the scope of the claims hereafter set forth.

Referring to the drawings, Figs. 1 and 2 illustrate the initially formed airfoil or blade blank prior to the warping operation in the present warping fixture.

The said blade consists of an elongated body having opposed upright side walls 11 and 12 which are of airfoil configuration which converge towards their outer end. Said side walls are joined at 14 and form an integral part of the annular flange 15 at the end of the said blade blank. Upon the side of said flange opposite from the blade there is provided a cylindrical hub 16 which has an internal annular recess 17 and a central axially extending shank 18, for illustration.

The opposite end of the blade blank terminates in the central axial extension 19 which provides a means for mounting and supporting the finally formed air foil or vane or blade within a portion of a supporting element such as the stator body of a compressor or turbine or other type of engine.

Fig. 3 fragmentarily illustrates at 19' the initial longitudinal axis of the blade blank, whereas the dotted lines 20 and 21 which centrally intersect indicate the new intersecting longitudinal axes of the respective twisted portions of the blade body after it has been drawn through the present warping fixture.

The said warping fixture hereafter described, with respect to Figs. 4, 5, 6 and 7, includes an elongated rectangularly shaped sturdy base 22. At one end of said base and mounted thereon adjacent the opposite marginal portions thereof are a pair of I-beam supports 23 which are arranged in opposed spaced relation, both supports being illustrated in the drawing. These supports are immovably anchored to base 22 by the securing bolts 24.

Mounted upon the top surface of each of the said supports 23 are respectively secured air cylinders 25, both of which are shown in Figs. 4 and 7, whose bottom flange

26 is secured to support 23 as by the fastening bolts 27. These cylinders could be hydraulic.

Compressed air supply pipe 28 fragmentarily illustrated, is joined at one end to the outer end of the cylinder 25 as at 28'.

There is a corresponding conduit 28 indicated in dotted lines in Fig. 4 which is adapted to join the opposite outer end of the second air cylinder 25 secured upon the opposite side of base 22 in opposed relation to the above described cylinder 25. The conduits 28 join the T fitting 29 which extends from control valve 30 which is supplied pressure fluid, either liquid or compressed air, through the conduit 31 fragmentarily shown, and which valve has a control element 32 whereby fluid under pressure may be directed to the outer ends of the respective cylinders 25 as desired for effecting forceful inward movements of the respective pistons 34 within the said cylinders.

Each of the said cylinders has an inwardly directed central guide sleeve 33 forming a part thereof through which slidably projects piston rod 36 or 52, the latter being joined at its outer end to the piston 34 within cylinder 25.

Coiled spring 35 shown in dotted lines surrounds piston rod 36 and is interposed between the inner wall of cylinder 25 and said piston normally retaining the same in its outermost position. However, referring to Fig. 4, with the rollers 45 and 53 in operative position, actually the pistons 34 would be moved inwardly of the cylinders 25 against the action of springs 35. It, therefore, follows that upon release of fluid pressure trapped within conduits 28, the said pistons 34 in their respective cylinders would be automatically returned to an inoperative or retracted position.

The piston rods 36 are slidably positioned loosely through the upright support 38 which is mounted upon base 22 inwardly of the respective cylinder with its flange 39 secured by the bolts 40 to the main base 22, as indicated in Fig. 7.

The outer end of piston rod 36 has secured thereto as by a pin or other structure the fitting 41 which is threaded as at 42 within and joined to the recumbent U-shaped or bifurcated roller support or yoke 43.

Roller support 43 has a central upright recess 44 within which is positioned the upright preformed idler warp roll 45 which is loosely journaled and supported in an upright position upon the mounting pin 46. This pin extends down through an outer portion of yoke 43, loosely through roller 45 and with the end of said pin nested within a corresponding recess 48 in the lower portion of yoke 43. Set screw 47 extends transversely through a portion of yoke 43 and is adapted to anchor the pin 46 in the position shown in Fig. 7.

By this construction with the set screw loosened, the pin may be removed so that different sizes and shapes of warping rolls 45 may be easily interchanged for a particular warping job.

The yoke 43 above and below piston rod 36 and spaced therefrom carries a pair of horizontally disposed guide bars 49 which are suitably secured to said yoke and which extend rearwardly thereof and slidably through the corresponding bushings 50 carried within upright support 38 to thereby provide a more effective and rigid mounting for yoke 43 and to further guide yoke 43 and maintain the same in the upright position shown.

While the present drawings do not illustrate in detail the second cylinder 25 which is arranged in opposed relation with respect to cylinder 25 shown in Fig. 4, nevertheless, the present invention contemplates this second cylinder as above mentioned, and which has projecting therefrom the reciprocal piston rod 52 which carries at its outer end a second oppositely arranged yoke 51 which is of the same construction as yoke 43 and operates in the same manner under the control of the second cylinder.

The yoke 51 carries a second upright warp roll 53 which is of a shape complementary to the shape and curvature of

corresponding wall of the airfoil and is adapted to operatively engage one side of the blade blank, for example, surface 12 of Fig. 2. It is understood that roll 45 would thus engage the opposite side 11 of said blade blank, and 5 is of a shape corresponding to the adjacent wall of said blank.

In normal operation, the amount of pressure to be applied to the said rolls depends upon the type of blade to be warped, its construction and the material from which 10 it is made, and its hardness. Accordingly, it is contemplated as a part of the present invention that the pressure to be applied to the piston rods may be varied. For illustration, in a normal warping operation the pressure applied may be to the extent of 700 pounds per square 15 inch, inasmuch as it is necessary during and throughout the warping operation that equal pressures be applied to opposite sides 11 and 12 of the blade blank as it is drawn through the said rolls.

It is contemplated that the cross-sectional shape of the 20 blade blank may be preformed with the said rolls 45 and 53 serving to operatively engage such preformed surfaces during the warping operation.

On the other hand, it is contemplated that the present 25 apparatus might be employed for actually forming partially or fully the cross-sectional shape of the blade as it is drawn through the rolls 45 and 53.

As shown in Fig. 7, there is provided a second pin 54 of the same construction as pin 46 for loosely supporting and journaling roll 53, and here also this pin is secured 30 in operative position by a set screw 47, and upon loosening said set screw may be removed to permit changing of the particular roll 53.

Referring to Figs. 4 and 5, intermediate the ends of the 35 base 22 and centrally thereof, there is provided an upright standard 55 which is suitably secured to the base as by the bolts 56.

The upper part of said standard carries the support 57 which retains a pair of aligned bearing supports or bushings 58 and 59 through which slidably extends the drawbar 60 which is of generally cylindrical shape, and by 40 which the said blade will be drawn through the said rolls in the manner hereafter described.

The outer end of said drawbar has an upright transverse slot 61 formed therethrough adapted to receive 45 the adapter locating key 62 which is secured by the screw 63 to a portion of drawbar 60 and extends thereabove. The adapter sleeve 65 loosely extends over the outer end of drawbar 60 and has an axial slot 64 therein adapted to cooperatively receive key 62 for effecting a correct 50 registry of said adapter with the drawbar and to align the transverse apertures in the sleeve with a corresponding aperture in the drawbar for cooperatively receiving the tapered locking pin 66 by which the adapter is immovably secured to the drawbar.

Said adapter, towards its outer end, has an annular 55 enlarged shoulder 67 and in its end face and formed therein a pair of transverse elongated slots 68 and 69 of rectangular shape in cross-section. Within these slots are positioned a pair of elongated oppositely arranged clamping fingers 70 which are secured within the said slots by the screws 71 which extend into portions of the adapter. Along the inner longitudinal edges of clamp fingers 70 are a pair of oppositely arranged inwardly directed vane engaging flanges 72 which extend around the flange 15 of the blank 11-12 for immovably securing the same with respect to the adapter and to thereby assure longitudinal withdrawing movement of the vane with the drawbar 60. It is important in inserting the blank that its longitudinal axis through the center of gravity be in alignment with the longitudinal axis of the drawbar, after which it is fixed in position and retained by clamp fingers 70 or other anchoring means.

Adjustable stop 73 shown in Fig. 9 is secured around a portion of drawbar 60 adjacent adaptor 65. Said stop 75 includes a pair of opposed semi-circularly shaped ele-

ments 74 and 75 which are secured together by the transverse fastening screws 75'. By this construction the stop 73 may be longitudinally adjustable upon draw bar 60 and secured in the desired position thereon. The resilient preferably rubber bumper stop 76 is mounted around draw bar 60 and is retained against longitudinal movement by stop 73. This bumper is adapted to cooperate with the end face of bushing 58 for limiting the withdrawing rearward movements of draw bar 60.

A second stop ring 73 is secured to said draw bar adjacent its opposite end and is adapted to cooperatively engage the end face of bushing 59 for limiting return movements of said draw bar. The inner end face of draw bar 60 has an axial bore which is interiorly threaded and is adapted to receive the reduced threaded end 74' of shoulder bolt 10. Said shoulder bolt has a reduced cylindrical portion 77 which cooperatively extends through the bushing 78 upon the interior of draw bar block 79, there being a pair of thrust washers 7 mounted upon portion 77 of the shoulder bolt cooperatively engaging opposite sides of draw bar block 79.

Operating arm 80 is horizontally disposed and at its outer end is pivotally mounted by shoulder screw 80' upon the upper end of the upright support 81 whose bottom flanged base 82 is secured to base 22 as by the bolts 83.

Intermediate the ends of arm 80 there is provided an elongated transverse upright slot 84 through which downwardly extends the shoulder screw 6, with a suitable bushing interposed if desired, said shoulder screw threadedly engaging drawbar block 79 as at 8.

The operating arm 80 terminates at its outer free end in the operating handle 85. By this construction the operating arm may be manually actuated in a horizontal plane about its pivot point 80' for effecting longitudinal reciprocal movements of said drawbar. It is contemplated, however, that power means may be employed for effecting such pivotal movements of operating arm 80, or for directly moving the drawbar.

Various types of operating arms may be provided such as will effectively engage the drawbar block 79 and permit fastening of the operating arm thereto for the purpose of producing longitudinal reciprocal movements of the drawbar.

As shown in Figs. 4 and 5, there is arranged upon base 22 an inclined cam block 86 which is preferably rectangular in cross-section and which carries upon one of its outer upright faces the elongated rectangularly shaped flat cam face 87 which is secured to the block by the screws 87', Fig. 6.

It is contemplated that the cam face may be angularly adjusted as desired, with respect to a vertical plane through the drawbar, depending upon the amount of twist to be made in the blade to be warped. For this purpose the block 86 is mounted upon the base 22 and secured thereon in a predetermined angular position.

There is also provided in conjunction with the said block suitable clamps of any desired construction which will effectively retain the said block in any desired position of angular adjustment.

In the preferred embodiment of the invention there is provided a block 90 upon base 22 and which is secured thereon by the fastening screw 91. Elongated clamping strap 92 with central elongated slot 93 is positioned over the upright bolt 94 which is secured to base 22 as at 94', Fig. 5. Said bolt at its upper end extends through slot 93 and has threaded thereover the nut 95 which operatively engages strap 92. One end of said strap depends as at 96 for supporting engagement with block 90. The opposite depending end 97 of said strap retainingly engages block 86. Consequently, tightening of the nut 95 will effectively secure the cam block in the desired position of adjustment.

Transversely arranged angular reference block 98 is secured upon base 22 in any suitable fashion and is

adapted for setting the angularity of block 86, using a protractor, for illustration, for securing the correct angle.

Said rotary control arm 99 shown in Figs. 5 and 6 is bifurcated at its upper end and is adapted to engage 5 a pair of oppositely arranged upright slots 101 formed in the surface of drawbar 60 adjacent its one end, there being provided a suitable locking plate 100 for effectively securing the depending control arm 99 rigidly with respect to said drawbar and for movement in unison therewith.

10 The lower end of arm 99 has a ball support 102 with a conical recess 103 therein adapted to cooperatively receive the hardened ball bearing 104. Sleeve 105 extends around said ball bearing and has mounted thereover the ball retainer 106 which is bolted to element 102 as by the bolts or screws 107, Fig. 6.

The ball 104 is thus retained upon the lower end of arm 99 and its outer surface projects laterally of retainer 106 for cooperative engagement with the cam face 87.

15 As is clear from Fig. 4, upon rotary movement of operating arm 80 by its handle 85 or by power means in order to effect a withdrawing movement of draw bar 60, the depending arm 99 and its ball 104 will cooperatively engage said cam plate in such a fashion that during said rearward movement the ball will respond to the inclined surface of the cam face 87 and thereby effect a predetermined arc or rotation upward to the said arm 99, and accordingly, rotary movement of draw bar 60.

20 It is contemplated that the amount of twist to be applied to a particular vane will vary, depending upon the particular stage to which the vane is to be applied, and accordingly, the angularity of the flat cam face 87 may be varied as desired.

25 In view of the inherent resiliency of the material employed, in operation it is normally contemplated that the rotary movement will be in excess of the amount desired, inasmuch as the metal will have a tendency to return slightly.

30 Thus there has been provided in conjunction with the present invention a device whereby a pair of oppositely arranged preformed and mating rolls will operatively engage opposite sides of a preformed vane blank and will compressively engage the same as the said blade is rearwardly withdrawn by drawbar 60, utilizing operating arm 80. At the same time, the cam plate 87 through the arm 99 will control the amount of rotary movement or twist which will be applied to the drawbar and, concurrently, the vane blank as it is drawn through the cooperating rolls.

35 40 The rolls 45 and 53 in a preferred embodiment are constructed of brass, or may be made of any other metal of less hardness than steel.

45 50 It is contemplated as an alternative to replacing merely the rolls 45 and 53 for different sizes and shapes of blanks that on the other hand, the entire yokes 43 and 51 may be interchanged, or portions of such yokes.

55 60 In Figs. 8 and 11 there is shown a different form of collet or adapter for securing a blade blank without a flange. The adapter 108 has an axial bore receiving the end of drawbar 60 and is secured thereto by the transverse tapered pin 111.

65 Key 62 secured to bar 60 guidably extends into axial slot 110 in adapter 108. The enlarged annular head 112 of the adapter has a bore 113 in its end face within which are a pair of spring biased blade gripping lugs 114 pivotally mounted within bore 113 as at 115.

70 75 The inner edges 116 and 117 of the lugs are shaped to correspond to the outer curvature of the leading end of the airfoil blank to thereby provide an effective means for grippingly engaging an airfoil blank of the type which has no securing flange.

75 It is contemplated furthermore that adapter 108 is interchangeable with adapter 65, or for that matter, any other type of special adapter which may be used for a

specific blade warping operation or for the various stages of blades which may be employed.

Fig. 12 fragmentarily illustrates a different means for reciprocating bar 60' and employs upon support 55 a cylinder 118 through which drawbar 60' slidably and rotatively extends as at points 119.

Piston 120 is secured to bar 60' within cylinder 118 and is responsive to pressure fluid supplied through either of the pipes 121 or 122 from the four-way control valve 123. This valve is joined to a source of pressure fluid or compressed air as indicated at 126. The control valve has a movable valve element 124 responsive to control 125 for switching supply and exhaust connections to the opposite ends of cylinder 118, to thereby provide a motor mechanism for effecting the reciprocal movements of drawbar 60'.

Having described my invention, reference should now be had to the claims which follow for determining the scope thereof.

I claim:

1. A blade warping fixture comprising a horizontal base, a pair of spaced opposed motors secured upon the base, oppositely arranged aligned piston rods reciprocally projecting from said motors, yokes upon the outer ends of said piston rods, complementary formed rolls loosely journaled upon upright axes within said yokes adapted to operatively and compressively engage opposite side walls of a horizontally disposed upright airfoil blade blank upon energization of the motors, an upright support upon said base, an elongated horizontally disposed draw bar slidably and rotatively mounted upon said support extending at right angles to said piston rods, lying in a general plane intermediate said rolls and adapted for connection to said airfoil blank, means mounted upon said base connected with said drawbar for longitudinally moving the same while permitting rotary movement thereof, a control arm rigidly secured to said drawbar and depending therefrom, an elongated cam plate secured upon said base having a cam face lying in an upright plane at a predetermined angle with respect to and intersecting at upright plane passing through the drawbar axis, the lower end of said control arm operatively engaging said cam face and responsive to lateral thrust to effect a predetermined rotary movement of said drawbar as it is moved longitudinally of said cam face, an upright standard secured on the base spaced from said support, said drawbar moving means including a horizontally disposed arm pivotally mounted at one end upon said standard, means upon its other end for effecting horizontal arcuate reciprocal movements thereof, a drawbar journal block loosely mounted upon the adjacent end of said drawbar, and means intermediate the ends of said arm and loosely supported thereby and secured to said drawbar block whereby the drawbar is free to rotate during longitudinal movements thereof.

2. A blade warping fixture comprising a horizontal base, a pair of spaced opposed motors secured upon the base, oppositely arranged aligned piston rods reciprocally projecting from said motors, yokes upon the outer ends of said piston rods, complementary formed rolls loosely journaled upon upright axes within said yokes adapted to operatively and compressively engage opposite side walls of a horizontally disposed upright airfoil blade blank upon energization of the motors, an upright support upon said base, an elongated horizontally disposed drawbar slidably and rotatively mounted upon said support extending at right angles to said piston rods, lying in a general plane intermediate said rolls and adapted for connection to said airfoil blank, means mounted upon said base connected with said drawbar for longitudinally moving the same while permitting rotary movement thereof, a control arm rigidly secured to said drawbar and depending therefrom, an elongated cam plate secured upon said base having a cam face lying in an upright plane at a predetermined angle with respect to and intersecting an upright plane passing through the drawbar axis, the lower end of said control arm operatively engaging said cam face and responsive to lateral thrust to effect a predetermined rotary movement of said drawbar as it is moved longitudinally of said cam face, a laterally arranged ball bearing socket at the lower end of said control arm, a ball bearing in said socket, means loosely retaining said ball bearing, said bearing being laterally engageable with said cam face, whereby during withdraw-

plane passing through the drawbar axis, the lower end of said control arm operatively engaging said cam face and responsive to lateral thrust to effect a predetermined rotary movement of said drawbar as it is moved longitudinally of said cam face, an upright standard secured on the base spaced from said support, said drawbar moving means including a horizontally disposed arm pivotally mounted at one end upon said standard, means upon its other end for effecting horizontal arcuate reciprocal movements thereof, a shoulder bolt removably mounted upon the end of the drawbar axially thereof, an apertured drawbar journal block loosely journaled upon said bolt, said arm having an elongated slot therein intermediate its ends, and a shoulder screw mounted on said arm loosely extending through said slot and threaded into said block.

3. A blade warping fixture comprising a horizontal base, a pair of spaced opposed motors secured upon the base, oppositely arranged aligned piston rods reciprocally projecting from said motors, yokes upon the outer ends of said piston rods, complementary formed rolls loosely journaled upon upright axes within said yokes adapted to operatively and compressively engage opposite side walls of a horizontally disposed upright airfoil blade blank upon energization of the motors, an upright support upon said base, an elongated horizontally disposed drawbar slidably and rotatively mounted upon said support extending at right angles to said piston rods, lying in a general plane intermediate said rolls and adapted for connection to said airfoil blank, means mounted upon said base connected with said drawbar for longitudinally moving the same while permitting rotary movement thereof, a control arm rigidly secured to said drawbar and depending therefrom, an elongated cam plate secured upon said base having a cam face lying in an upright plane at a predetermined angle with respect to and intersecting at upright plane passing through the drawbar axis, the lower end of said control arm operatively engaging said cam face and responsive to lateral thrust to effect a predetermined rotary movement of said drawbar as it is moved longitudinally of said cam face, there being a laterally arranged ball bearing socket at the lower end of said control arm, a ball bearing in said socket, means loosely retaining said ball bearing, said bearing being laterally engageable with said cam face, whereby during withdraw-

ing movements of said drawbar, said ball and its arm will be swingingly elevated.

4. A blade warping fixture comprising a horizontal base, a pair of spaced opposed motors secured upon the base, oppositely arranged aligned piston rods reciprocally projecting from said motors, yokes upon the outer ends of said piston rods, complementary formed rolls loosely journaled upon upright axes within said yokes adapted to operatively and compressively engage opposite side walls of a horizontally disposed upright airfoil blade blank upon energization of the motors, an upright support upon said base, an elongated horizontally disposed drawbar slidably and rotatively mounted upon said support extending at right angles to said piston rods, lying in a general plane intermediate said rolls and adapted for connection to said airfoil blank, means mounted upon said base connected with said drawbar for longitudinally moving the same while permitting rotary movement thereof, a control arm rigidly secured to said drawbar and depending therefrom, an elongated cam plate secured upon said base having a cam face lying in an upright plane at a predetermined angle with respect to and intersecting an upright plane passing through the drawbar axis, the lower end of said control arm operatively engaging said cam face and responsive to lateral thrust to effect a predetermined rotary movement of said drawbar as it is moved longitudinally of said cam face, a laterally arranged ball bearing mounted upon the lower end of said control arm engageable with the said cam face, said drawbar having a pair of opposed upright slots formed therein in its outer face, the upper end of said arm having an upright yoke structure

received by said slots for fixedly securing said drawbar and arm together.
